UNITED STATES PATENT OFFICE.

LOUIS MARINO CASELLA, OF LONDON, ENGLAND.

PRINTING-TELEGRAPH INSTRUMENT.

SPECIFICATION forming part of Letters Patent No. 673,381, dated May 7, 1901.

Application filed August 10, 1900. Serial No. 26,479. (No model.)

To all whom it may concern:

Be it known that I, LOUIS MARINO CASELLA, a subject of the Queen of Great Britain and Ireland, residing at London, England, have 5 invented a new and Improved Printing-Telegraph Instrument, (for which I have made application for Letters Patent in Great Britain under No. 5,382, dated March 21, 1900,) of which the following is a specification.

10 This invention relates to printing-telegraph instruments in which a type-wheel is set in a known manner so as to bring a required letter in position for printing; and it consists, essentially, of a control device in a 15 local relay-circuit by which the printing mechanism is set into operation upon the cessation of the alternating circuit by which the type disk or disks have been set in the required position for printing.

20 Figure 1 is an outside view of the complete instrument, showing the ordinary printing mechanism. Fig. 2 is a transverse section through the instrument on line X Y, Fig. 1. Fig. 3 is a plan of the instrument. Fig. 4 is a 25 further plan of the instrument, showing more clearly the printing-lever and its return-lever. Fig. 5 is an elevation of the printing-lever and its return-lever with the intervening side removed. Fig. 6 is a detached elevation of 30 the armature. Fig. 7 is a diagram of the circuits and connections to the parts of the said instrument. Fig. 8 is a detached detail of the control-fork, showing different positions. Fig. 9 is an end and side elevation of the type- 35 disk-setting mechanism detached. Fig. 10 is an end view of printing magnets and armature. Fig. 11 is an end and side elevation of rocking piece detached and enlarged.

I will first refer to those parts of the instrument which are essential parts of such an instrument and necessary for the understanding of the action of the instrument; but as such main parts are of usual type and no essential part of my present invention I will 45 not describe such parts in detail, but only refer to their position and general effect.

40 *a* is a set of electromagnets having permanent magnets *b* placed over their poles, causing such electromagnets in a well-known way 45 to vibrate a pivoted armature *c* for every alternation of an alternating circuit passed through such magnets from a transmitter.

These electromagnets *a* are the only electromagnets in the alternating circuit 11, Fig. 7, from the transmitting-station. The oscillations of the armature *c* are transmitted by an arm *c*² through the well-known pivoted anchor-pallet *d*' and step-wheel *d*, as shown in detail in Fig. 9, to the type wheel or wheels *e*, having an inking wheel-pad *e*'. The oscillation of the pallet *d*' sets the type-wheel *e* to any desired letter over the printing-line, according to the number of transmitted alternate impulses from the line-wire, operated conveniently by a hand or Wheatstone transmitter in a manner well known.

f f are the printing-electromagnets, which are in a local relay-circuit 2 2, Fig. 7, energized by a battery conveniently placed in a case under the instrument. Such electromagnets when energized by the local circuit operate a pivoted printing-lever *g* by their armature *g*' engaging in the end of the printing-lever *g*, and thus pressing the paper (not shown) in the usual way up against the under face of the type wheel or wheels *e* when the latter are set and at rest.

The above being common elements in any printing-telegraph instrument, the object of the present invention is to design a control 80 from the transmitted alternating current, so that the local relay printing-circuit shall remain broken so long as the alternating current is passing for the setting of the type-wheels *e* and shall become closed so soon as 85 the alternating current ceases, when the type-wheel *e* has been set, thus effecting the rise of the printing-lever *g* and the printing at the proper time, the ultimate rise of the printing-lever *g* once more breaking the local 90 circuit and permitting all parts to fall back into their original position for the next transmission. To effect this, I continue the end of the oscillating armature *c* by a rod *c*', which, engaging in the bottom of a pivoted 95 rocking piece *h*, Fig. 2, causes a projecting nose *h*' of this rock-piece to vibrate rapidly between the arms of the fork *k*, Fig. 2. The said rocking piece *h* and the fork *k* are insulated (see Figs. 11 and 5) and are each of 100 them a terminal in the local battery-circuit 2 2, Fig. 7, which circuit includes the printing-electromagnets *f f*. The rocking piece *h* is pivoted on an insulated bracket *h*² at the

top of a transverse diaphragm of the box, and the fork *k* is also hinged upon an insulated hinge *x* on the bottom and other side of the said diaphragm of the box.

5 Although the nose *h'* of the rocking piece *h* is constantly making alternate contacts with each side of the fork *k* all the time the alternating current is passing, the contact is so instantaneous that no effective current 10 passes through the electromagnets *ff* until the alternating current has ceased and the nose *h'* of the rocking piece *h* rests for an appreciable period upon one or other of the arms of the fork *k*. The printing-magnets 15 are thus energized and the printing takes place.

The printing-lever *g* operates from its rising end by a link *l* a return-lever *m*, which on the descent of its farther end carries, attached thereto, a triangular piece *n*, Fig. 2, which still further insures and accentuates the contact of the nose *h'* against that arm of the fork *k* upon which it rests, and finally upon the completion of the downward stroke 25 of the lever *m*, which is the completion of the upward stroke of the printing-lever *g*, the end of the lever *m* strikes the end of a transverse lever *p*, Fig. 2, which, rising at its farther end, strikes a tappet *q* of the fork *k*, 30 which is pivoted at the bottom on a horizontal pivot-pin *r*, so that the fork is thrown right back away from contact with the nose *h'* of the rocking piece *h*. The local circuit is thus again broken. The printing-lever *g* 35 falls by its own weight into normal position, and the fork *k*, by a recoil-spring *s*, attempts to come back to its original position on either side of the nose *h'*. This, however, it cannot do at once, or the local circuit would be again 40 made, but is prevented from doing so by striking against the insulated tip *t* of the nose *h'*. So soon as the alternating circuit is again started the vibration of the nose *h'* allows the

fork *k* to come to its proper vertical position on either side of the nose *h'*, and all is then 45 ready for a sequence of the operations for printing when the alternating current has ceased once more.

Having now described this invention, what I claim, and desire to secure by Letters Patent, is—

1. In combination in a printing-telegraph instrument, a vibrating armature two electromagnets in a transmitted alternating current; an extension of said vibrating armature connected as an insulated terminal in a relay-circuit; and a divided contact, also connected as an insulated terminal in said relay-circuit, situated on either side of said vibrating extension; the vibrating contact being ineffective to close the relay-circuit and to energize the printing-electromagnets therein, until the transmitted alternating current ceases, and the vibrating extension is at rest upon one part or other of the divided contact. 60

2. In combination in a printing-telegraph instrument, a vibrating armature two electromagnets in a transmitted alternating current; an insulated and pivoted metallic nose, rocked thereby; an insulated tip to said nose; an insulated and hinged fork or divided contact, situated normally on either side and within reach of said metallic rocking nose; a pivoted printing-lever operated by the armature of the printing-magnets 2; and means operated by printing-lever to remove said hinged fork from contact with said pivoted metallic nose, to break the local circuit, when the printing stroke has been completed, substantially as described. 75

In witness whereof I have hereunto set my hand in presence of two witnesses.

LOUIS MARINO CASELLA.
